DESIGN FOR A COMBINED ERASER AND PENCIL TIP

Michael Pipi, Jersey City, N. J., assignor to Joseph Dixon Crucible Company, Jersey City, N. J., a corporation of New Jersey

Application January 18, 1938, Serial No. 74,388

Term of patent 14 years

To all whom it may concern:

Be it known that I, Michael Pipi, a citizen of the United States, and a resident of Jersey City, in the county of Hudson and State of New Jersey, have invented a new, original, and ornamental Design for a Combined Eraser and Pencil Tip, of which the following is a specification, reference being had to the accompanying drawing, forming a part thereof and in which:

Fig. 1 is a front elevation of the combined eraser and pencil tip embodying my design, the reverse side of the eraser and holding tip therefor being substantially the same in appearance as the side shown;

Fig. 2 is a side elevation of the combined eraser and holding tip shown in Fig. 1; and

Fig. 3 is a top plan of the parts shown in Figs. 1 and 2.

I claim:

The ornamental design for a combined eraser and pencil tip as shown and described.

MICHAEL PIPI.
